UNITED STATES PATENT OFFICE.

MARIUS A. BAUER, OF WORCESTER, MASSACHUSETTS, ASSIGNOR TO M. J. WHITTALL ASSOCIATES, A VOLUNTARY ASSOCIATION OF MASSACHUSETTS.

FILLING FORK AND STOP MOTION FOR ORIENTAL RUG LOOMS.

Application filed May 18, 1927. Serial No. 192,445.

This invention relates to a filling fork and stop motion particularly designed for use on an oriental rug loom of the general type shown in the Renard Patent No. 894,287.

5 These looms operate by inserting and heating up two successive picks of filling; after which the lay and reed remain stationary while a row of yarn tufts are inserted and knotted about the warp threads. After a 10 full row of tufts is inserted, two more picks of filling are inserted and beaten up.

It is one object of my invention to provide a filling fork and stop motion for such a loom, so constructed that the loom will be promptly 15 stopped in the absence of filling. Provision is also made for stopping the loom upon failure of the shuttle to box.

A further object is to provide means for 20 clamping and tensioning the filling thread by the filling fork while it is being beaten up, and for momentarily relieving the tension as the lay moves backward after the beating in of the second pick of filling, so that the filling 25 will remain close to the fell of the cloth, permitting the yarn tufts to be inserted in the required position.

30 My invention further relates to arrangements and combinations of parts which will be hereinafter described and more particularly pointed out in the appended claims.

A preferred form of the invention is shown in the drawings, in which

35 Fig. 1 is a front elevation of a portion of a loom having my improved stop motion applied thereto;

Fig. 2 is an end elevation of the parts shown in Fig. 1, taken along the line 2—2 in Fig. 1.

Fig. 3 is a sectional end elevation, taken along the line 3—3 in Fig. 1;

40 Fig. 4 is a detail plan view of a portion of the lay and filling fork, looking in the direction of the arrow 4 in Fig. 3;

Fig. 5 is a sectional elevation, taken along the line 5—5 of Fig. 4;

45 Fig. 6 is an end elevation of certain parts of the stop motion with the lay shown in section;

Fig. 7 is an end elevation, showing certain of the parts in Fig. 2 in a different operative 50 position;

Fig. 8 is a sectional plan view, taken substantially along the line 8—8 in Fig. 2, and

Figs. 9 to 13, inclusive, are detail plan

views, illustrating successive steps in the operation of the filling fork and stop motion. 55

Referring to the drawings, I have shown a loom comprising a frame 20 (Fig. 2) on which a lay 21 is mounted to oscillate in the usual manner. A filling fork 22 is provided at each end of the lay 21, as indicated in Fig. 60 9, said filling forks being connected to move simultaneously and to operate together. A description of the operation of one of the forks will apply equally to the operation of the other. 65

Each filling fork 22, as indicated in Figs. 3 to 5, comprises a sliding support 25 having a plurality of rods or fingers 26 projecting rearwardly therefrom. Each plate 25 is slidable vertically in a slot 27 in the lay end 70 or plate 28 forming the bottom of the adjacent shuttle box. The lay end or plate 28 is also provided with transversely extending slots 29, through which the rods or fingers 26 will pass freely if no filling F is interposed 75 beneath the fork.

When the filling is in its normal position, as shown in Figs. 4 and 5, the fork will remain in the position indicated in Fig. 5 but will exert substantial tension upon the filling F 80 while it is being beaten up to the fell of the cloth C.

Each sliding plate 25 (Fig. 6) is pivotally connected at its lower end to a link 30, which in turn is pivoted to the forwardly projecting end of an arm 31 fixed on a rock shaft 32. A spring 33 is connected at its forward end to each link 30 and at its rear end to a pin 34 (Fig. 3) fixed on the shaft 32 or on the hub 35 of the arm 31. The spring 34 acts 90 to yieldingly restore the parts from the forward dotted line position shown in Fig. 3 to the rearward full line position as the lay moves back.

An arm 38 (Fig. 2) projects forward from the rock shaft 32 and rests upon a bent lever 39 (Fig. 1) pivoted at 40 on the loom frame 20, having a stud 41 resting upon a collar 42 fixed on an intermittently rotating shaft 43. The collar 42 is provided with a series of cam lugs 44, 45 and 46 which successively engage the stud 41, momentarily raising the lever 39 and the arm 38, and rocking the shaft 32, thus swinging the arms 31 and raising the filling forks. It will be noted that the lug 46 is of less height than the lugs 44 and 100 105

45 and that it consequently does not raise the filling fork as high as the other two lugs for a reason to be explained.

An arm 50 (Fig. 2) projects rearward from the rock shaft 32 and is pivotally connected at 51 to an upright rod 52 projecting freely through an opening in the rear end portion of a stop motion lever 53 pivoted at 54 on the loom frame. A nut 55 is threaded on the rod 52 and forms an abutment to engage the lever 53 when the filling fork drops through the slots 29 in the lay upon absence of filling. A stud 56 (Figs. 2 and 8) on the lever 53 extends through a long segmental slot 57 in a lever 58 which is pivoted at 59 on an arm 60 secured to a shaft 61. A handle 62 projects forward from the lever 58 and normally counterbalances the rear portion of the lever 58 and also the forwardly projecting portion 20 of the lever 53. Adjustable weights 63 (Fig. 2) may be provided on the rear end of the lever 53 for the same purpose.

The lever 58 is provided at its rear side with a lug or projection 65 (Fig. 8) adapted to be engaged by a shoulder 66 (Fig. 2) on a disc 67 mounted to rotate intermittently on a shaft 68.

The upper end of the arm 60 is notched as indicated at 68^a in Fig. 7 and normally engages a stud or roll 69 (Fig. 2) in the rear end of a lever 70 mounted on a fixed pivot 71. A spring 72 connected by a link 73 to the lever 70 causes the roll 69 to be firmly seated in the notch 68.

35 The shaft 61 (Fig. 7) is provided with an arm 75 having a stud 76 positioned in a slot 77 in a lever 78 mounted on a fixed pivot 79. The lower end of the lever 78 is connected by a link 80 to a clutch lever 81 having a fork 40 82 engaging a yoke 83 in a clutch collar 84.

So long as the filling extends under one or the other of the filling forks 22, the fork will be held in such a position that the nut 55 on the rod 52 (Fig. 2) cannot engage the lever 53 and depress the stud 56. If, however, the filling is exhausted, the filling fork will descend to the position indicated in Fig. 6, depressing the stud 56, correspondingly depressing the lever 58 so that the projection 50 65 on the lever comes into the path of the shoulder 66 on the plate 67 and is moved rearward thereby, thus shifting the stop motion parts from the position shown in Fig. 2 to the stopping position shown in Fig. 7, and with 55 drawing the clutch 84 from engagement with its driving member.

It is also desirable to stop the loom when the shuttle fails to box, and for this purpose I have provided a bell crank 90 (Fig. 2) pivoted at 91 on a bracket 92 on the rear of the lay and engaging the back binder 93. A forwardly projecting arm 94 of the bell crank 90 is provided with a pin 95 resting on top of the lever 58 previously described.

65 When the shuttle is properly boxed, the pin

95 is raised and inoperative but if the shuttle fails to box, a spring 96 will draw the bell crank 90 forward, thus depressing the lever 58 and causing the stopping of the loom as previously described.

The operation of the parts during the ordinary running of the loom is best indicated in Figs. 9 to 13. The position of the parts during the insertion of a row of pile tufts is as indicated in Fig. 9, with the shuttle S in the left hand shuttle box. After the row of pile tufts is inserted, the shuttle is picked to the right hand position indicated in Fig. 10, the filling forks being raised by the cam lug 44 (Fig. 1) just at the time the shuttle is picked. The forks are immediately released and one of the forks falls upon the filling F, clamping it against the lay end plate 28 and applying tension thereto as the lay moves forward to the position shown in Fig. 11.

The lay then moves rearward and the filling forks are momentarily raised by the cam lug 45 (Fig. 1) while the shuttle is sent to the left hand box, as indicated in Fig. 12. The filling forks are again released, tensioning the filling during the forward movement of the lay as previously described.

It is necessary, however, to prevent the relatively heavy filling fork from dragging the filling rearward as the lay moves back and is about to come to rest, as it is essential that the filling remain beaten in closely against the fell of the cloth while the next row of pile tufts is being inserted. Accordingly, the third cam projection 46 (Fig. 1) raises the filling fork slightly, allowing the filling to slip forward under the fork as the lay moves rearward from the position shown in Fig. 12 to the position shown in Fig. 13. In this manner sufficient slack is provided to prevent pulling the filling away from the fell of the cloth. The fork then falls again on the filling, before the lay reaches rearward position, thus preventing any more filling from being pulled out of the shuttle by the knotting-in of the tufts, which might cause an uneven edge.

From the preceding description, it will be seen that I have supplied the loom with an efficient filling stop motion, particularly adapted for use on an oriental rug loom, and that I have also arranged said stop motion so that it will tension the filling during the beat-up, and that I have particularly arranged to relieve the tension during the final movement of the lay to idle or inoperative position.

Having thus described my invention and the advantages thereof I do not wish to be limited to the details herein disclosed otherwise than as set forth in the claims, but what I do claim is:—

1. In a loom having alternate operative and inoperative periods for the shuttle, a pair of filling forks, means to raise said forks to permit passage of the shuttle, said forks be-

ing released and resting by gravity on the filling to tension said filling during the beating up thereof, and means to raise said forks to momentarily release the tension on the filling as the lay moves rearward just prior to its inoperative rest period.

2. In a loom having alternate operative and inoperative periods for the shuttle, a pair of filling forks, means to raise said forks to 10 permit passage of the shuttle for two successive picks, said forks being released and resting by gravity on the filling to tension said filling during the beating up thereof, and means to raise said forks to momentarily release the tension on the filling as the lay moves rearward after the second pick of filling is beaten up and just prior to the inoperative rest period of the shuttle.

3. In a loom having alternate operative and 20 inoperative periods for the shuttle, a pair of filling forks, means to raise said forks to permit passage of the shuttle for two successive picks, said forks being released and resting by gravity on the filling to tension said filling 25 during the beating up thereof, and means to raise said forks to momentarily release the tension on the filling as the lay moves rearward after the second pick of filling is beaten up and just prior to the inoperative rest 30 period of the shuttle, said fork-raising means thereupon becoming inoperative and releasing said forks to hold the filling during the period of rest of the shuttle.

4. In a loom having alternate operative and 35 inoperative periods for the shuttle, a pair of filling forks, means to raise said forks to permit passage of the shuttle, said forks being released and resting by gravity on the filling to tension said filling during the beating 40 up thereof, and means to raise said forks to momentarily release the tension on the filling as the lay moves rearward just prior to the inoperative rest period of the shuttle, said means comprising a rotating cam having 45 three cam lugs thereon, two of said lugs causing said forks to be lifted above a shuttle in flight and the third lug acting to lift said fork a relatively short distance only.

5. In a loom for weaving tufted fabric, 50 having tuft inserting mechanism, and, a lay, having a substantial period of rest during the operation of said tuft-inserting mechanism, in combination, a filling fork movable vertically through slots in said lay and resting freely 55 by gravity on the filling to tension said filling

during the beating up thereof, and means to momentarily lift said filling fork to relieve the filling tension and immediately thereafter to release said filling fork just prior to the beginning of said period of rest of said lay.

6. In a loom for weaving tufted fabric, a lay, and a filling fork movable vertically through slots therein and having fingers supported at their front ends, said fork resting 65 freely by gravity on the filling to tension said filling during the beating up thereof, and means to raise said fork and momentarily release the filling for forward movement thereof during rearward movement of said lay 70 and fork, said fork being then released to again engage and tension said filling before said rearward movement of the lay is completed.

7. In an oriental rug loom in which two 75 picks of filling are inserted, followed by an inactive period for the shuttle, in combination, a filling fork normally resting by gravity on the filling to tension the same, means to twice raise said fork substantially to permit 80 flights of the shuttle, and means to raise said fork slightly to allow the filling to slip relatively forward under said fork during final rearward movement of the shuttle, said latter means immediately releasing said fork as 85 such rearward movement is completed.

8. In a loom, a stop motion including a lever having a shoulder thereon, a rotating member having a lug effective to engage said shoulder and stop the loom, said lever being 90 normally inoperatively positioned with said shoulder out of the path of said lug, a filling fork, and means controlled thereby effective to move said shoulder from normal inoperative position into the path of said lug upon 95 absence of filling and thereby cause the loom to be stopped.

9. The combination in a loom as set forth in claim 8, in which said lever has a long arcuate slot and in which said controlling means includes an arm having a pin extending into 100 said slot and thus positioning said lever.

10. The combination in a loom as set forth in claim 8, in which additional means is provided to depress said lever if the loom shuttle fails to box.

In testimony whereof I have hereunto affixed my signature.

MARIUS A. BAUER.
